LOUIS G. KLEESPIES, OF SAN FRANCISCO, CALIFORNIA.

SCREEN.

1,122,767.

Specification of Letters Patent.

Patented Dec. 29, 1914.

Application filed May 26, 1914. Serial No. 841,015.

To all whom it may concern:

Be it known that I, LOUIS G. KLEESPIES, a citizen of the United States, residing at San Francisco, in the county of San Francisco and State of California, have invented new and useful Improvements in Screens, of which the following is a specification.

The object of the present invention is to provide an adjustable window screen which will eliminate flies and afford better ventilation than the screens at present in use.

In the accompanying drawing, Figure 1 is a side view of the screen; Fig. 2 is a vertical sectional view on the line 2—2 of Fig. 1; Fig. 3 is a similar view on the line 3—3 of Fig. 1; Fig. 4 is a horizontal sectional view on the line 4—4 of Fig. 1.

Referring to the drawing, 1 indicates a screen frame, which may be of wood, metal, or any suitable material. Its top 2 and bottom 3 are in sections, one section having a dove-tailed rib 4 slidable in a correspondingly shaped groove 5 in the other section. Thus the frame consists of two sections 25 movable horizontally to and from each other, each having one vertical side and two horizontal sides. In the inner edge of the vertical side 6 of each screen section is a groove 7, the width of which is slightly 30 more than one-third of the thickness of said vertical side, and in said groove are secured a series of cleats or clamping bars 8, 9, which clamp or wedge in the groove vertical edges of a series of screen sections.

35 One vertical edge of the lowermost screen section 11 of each frame section is held between the clamping bar 8 and the outer side of the groove 7. The next higher screen section 12 extends from a level about an 40 inch lower than the top of the lowermost section 11, and a lower main part *b* of the corresponding edge of said section is contained between the clamping bar 8 and the inner side of the groove 7; but the lowermost portion *a* of said edge is contained in an oblique groove 13 cut in the inner portion of the vertical side of the frame section. The extreme upper portion *d* of said edge of said screen section is contained between the clamping bar 9 and the outer side of the groove, while an upper intermediate portion *c* of said edge is contained in an oblique outwardly and upwardly extending slot or groove 14 formed by the oblique 45 parallel upper edge of the lower clamping bar 8 and lower edge of the upper clamping

bar 9. A vertical series of as many screen sections as may be desired may be used in the screen in this manner. The uppermost screen section has its corresponding edge clamped between the inner side of the groove 7 and the uppermost clamping bar 9, the lower marginal portion of said edge being, however, received in an oblique groove or slot 16 cut in the inner portion of the vertical side of the frame section.

The above described construction is the same for both frame sections and inasmuch as it is necessary that the screens of one frame section should slide inside those of the other frame section, the upper and lower edges of the uppermost and lowermost screen sections respectively are received in grooves 17, 18 formed in the inner edges of the respective horizontal members of the two frame sections. The other vertical edges of said screen sections are clamped in narrow folded metallic strips 20, said strips extending from the bottom of the screen sections, first, to the upper edges of the lowermost screen sections, then being bent downward to the bottoms of the next upper screen sections, and being then bent upwardly to the tops of said screen sections, and so on in like manner to the top of the screen. The upper edge of each screen section except the uppermost slides between, and is guided by, a bent portion of the metallic strip 20 clamping the edge of the corresponding screen section of the other frame section.

My improved screen tends to eliminate flies from a room in which it is used, for the tendency of the fly alighting on the screen is to walk upward thereon, and in doing so it eventually arrives at the opening between two screen sections, and, passing through said opening, is then outside the room. Moreover, my screen affords better ventilation, especially in calm weather when it is most needed, for, under such conditions, the only air currents are those produced by the heating or cooling of immediate objects, and in such cases they are vertical, and such air currents are very greatly obstructed by the old style of screen, whereas by my improved screen they are facilitated.

I claim:—

A window screen composed of sections and having the top and bottom made in sections slidable relatively to each other, each frame section having therein a vertical se-

ries of screen sections, the upper portion of each lower screen section extending above, and outside of, and being spaced from, the lower portion of each screen section above it, one vertical edge of each screen section being secured in the vertical member of the corresponding frame section, and a clamping member clamping the other vertical edges of each frame section, said clamping member forming guides for the horizontal

edges of the screen section of the other frame section.

In testimony whereof I have hereunto set my hand in the presence of two subscribing witnesses.

LOUIS G. KLEESPIES.
